UNITED STATES PATENT OFFICE.

GENERAL M. DITTO, OF JOLIET, ILLINOIS.

CONCRETE MOLD.

Application filed March 31, 1922. Serial No. 548,828.

To all whom it may concern:

Be it known that I, GENERAL M. DITTO, a citizen of the United States, residing at Joliet, in the county of Will and State of Illinois, have invented certain new and useful Improvements in Concrete Molds, of which the following is a specification.

The mold of this invention is designed primarily for the purpose of molding concrete slabs of a character at present used in the construction of corn cribs or like structures in which ventilating slots or openings are provided.

The object of the present invention is to so design and construct the mold that a plurality of such ventilating slots will be formed in the slab by the provision of removable core pieces suitably fitted within the body of the mold.

In the molding operation, it is customary to impart to the mold, during or immediately after the pouring operation, a sufficient degree of vibration to cause the liquid concrete to settle evenly and uniformly into the mold, and the core pieces are configured and mounted in such a manner as to conform to the requirements of this vibratory action in such a manner as to avoid the formation of thin fins or ribs of concrete within the joints between the cores and the body of the mold.

Further objects and uses of the invention will appear from a detailed description thereof, which consists in the features of construction and combinations of parts hereinafter described and claimed.

In the drawings:

Figure 1 is a top plan view of the mold;

Fig. 2 is a side elevation of the same;

Fig. 3 is an end elevation of the same;

Fig. 4 is a longitudinal sectional view of the mold, taken on line 4—4 of Fig. 1;

Fig. 5 is a cross sectional view, taken on line 5—5 of Fig. 4; and

Fig. 6 is a perspective view of one of the completed blocks.

The mold comprises a body portion having a floor 10, which in the particular form shown is depressed along one side 11 to mold the rib or tongue 12 in the completed slab, shown in Fig. 6. The metal of the floor at the outer edge of the depressed portion is upturned to furnish a side wall 13 terminating in an outwardly projecting upper edge flange 14. The edge flange furnishes a support for a longitudinally extending bar 15 which is provided with a pair of outwardly

projecting hooked fingers 16 which hook over the edge of the flange 14 and serve to suspend the bar 15 above the depressed floor 11 of the mold in position to mold the groove 17 in the completed slab. The floor on the opposite side, which stands at a higher elevation, is upturned to furnish a side wall 18 provided with a flange 19 which is engaged by hooked fingers 20 outstanding from a molding bar 21 of curved configuration along its inner edge, which bar serves to mold the rounded edge 22 of the completed slab.

The ends of the mold are closed by means of gates 23 which are secured by hooks 24 at their lower edges to a pair of supporting blocks 25, one at each end of the mold, which blocks also serve to support the ends of the floor. The gates at their ends are provided with inturned flanges 26, each of which terminates in an angularly disposed marginal flange 27 which affords a point of engagement for a latch 28 hooked to a fin 29 on the proximate side wall of the mold.

The floor of the mold is provided at recurrent intervals with a plurality of transversely extending sockets 30, each of which is secured to the floor of the mold by screws 31 or the like, and each socket on its upper edge is grooved or channeled to receive the rounded lower edge of a wedge shaped core block 32 which diverges upwardly in unequal degree, being set in oblique relation to the plane of the floor, which core blocks are configured to form the ventilating slots or openings 33 in the completed slab, which slots or openings extend in oblique relation through the slab, so as to shed the rain when the slabs are erected into a corn crib or like structure. Each core piece is provided in its rounded lower edge with a dowel pin 34 which extends vertically through openings in the socket and in the floor of the mold, the fit of the parts being sufficiently free to permit the core pieces to drop away from the mold when the mold is overturned to discharge the completed slab. The core pieces are preferably made of iron in order to afford the necessary weight to come away freely from the body of the mold.

In use, the side bars 15 and 21 are hooked in position on opposite sides of the body of the mold, and the desired number of core pieces are positioned in transverse relation to the body and within the sockets on the floor thereof, and the end pieces are then

closed and latched, after which the mold is ready to receive the fluid concrete or like plastic material. The mold is preferably supported upon a vibrating table or other 5 vibrating support, and the fluid material is poured into the mold while the same is being sharply vibrated to cause the fluid material to run evenly and uniformly into all portions of the mold. After the mold has 10 been filled to the upper level of the sides and ends, it is allowed to stand for a considerable period of time until the concrete or like plastic material has become set and hardened to the requisite degree.

15 In removing the completed slab, the end gates are unlatched, and the mold with the slab therein is then preferably overturned, which causes the cores and the molding bars 15 and 21 to drop away freely from the 20 body of the mold, the core blocks standing with their broad edges downwardly. Thereafter, upon lifting the completed slab, the core pieces will fall out and the operation is complete. By providing rounded socket 25 members to receive the rounded edges of the core blocks, any possibility of ingress of cement or other plastic material into the space between the core blocks and the sockets is avoided, since the vibration to which the 30 mold is subjected will merely cause the core pieces to rock slightly within the sockets afforded, without thereby opening up or enlarging the joint or crack at the point of juncture between the core piece and its 35 socket, so that ingress of material at this point is prevented. The arrangement is one which can be readily assembled and disassembled for use, and one which serves to produce slabs of sharp and perfect configuration 40 at a minimum of trouble and expense, and without the need for careful manipulation.

Although the device has been described with particularity as to detail, and although 45 the arrangement shown is one which has proven highly efficient in use, it is not the intention in the claims, unless otherwise indicated, to limit the invention to the precise details shown and described.

50 I claim:

1. A mold for plastic materials, comprising a body, a plurality of core pieces located within the body, and a socket member for each core piece secured to the body, each 55 core piece being removably supported within its socket, substantially as described.

2. A mold for plastic materials, comprising a body, a plurality of core pieces located within the body, and a socket member for each core piece secured to the body, each 60 core piece being removably supported with-

in its socket and configured to diverge outwardly away from the point of support, substantially as described.

3. A mold for plastic materials, comprising 65 a body consisting of a floor having side and end walls, a socket member secured to the floor of the body and grooved along its upper edge, and a core removably supported within the groove of the socket, substantially 70 as described.

4. A mold for plastic materials, consisting 75 of a body comprising a floor and side and end walls, a socket member secured to the floor of the mold and provided along its upper edge with an arcuately formed channel, and a core piece provided with a rounded edge removably fitted within said channel, substantially as described.

5. A mold for plastic materials, consisting 80 of a body comprising a floor and side and end walls, a socket member secured to the floor of the mold and provided along its upper edge with an arcuately formed channel, and a core piece provided with a rounded edge removably fitted within said channel 85 and configured to diverge upwardly from said rounded edge, substantially as described.

6. In a mold for plastic materials, comprising 90 a floor provided with side and end walls, a series of transversely arranged socket members secured to the floor and each provided on its upper edge with an arcuately formed groove or channel, a series of 95 wedge shaped core pieces having their lower edges rounded to fit removably within the arcuately formed grooves, and a dowel pin for each core piece and its associated member for holding the core against accidental 100 displacement, substantially as described.

7. In a mold for plastic materials, the combination of a body comprising a floor provided with a depressed portion along 105 one edge, said floor terminating in upstanding side walls, molding bars removably secured to each of the side walls, one of said molding bars being suspended to overlie the depressed floor portion, gates for the opposite ends of the body, a 110 plurality of socket members secured in parallel relation to the floor of the body and in transverse relation to the side walls, each socket member being arcuately channeled along its upper edge, a plurality of 115 downwardly converging wedge shaped core pieces, each having its lower edge rounded to fit removably within the associated socket, and a dowel pin for each core piece and socket for removably holding the core piece 120 within the socket, substantially as described.

GENERAL M. DITTO.
